(57) **CLAIM**

The ornamental design for a medical consumable device, as shown and described.

DESCRIPTION

FIG. 1 is a top view of the medical consumable device of the present invention;

FIG. 2 is a left side view thereof;

FIG. 3 is a right side view thereof;

FIG. 4 is a front view thereof;

FIG. 5 is a bottom view thereof; and,

FIG. 6 is a top, left perspective view thereof.

The broken lines in the drawings depict portions of the medical consumable device that form no part of the claimed design.
